ANTIDEFLECTION ROLL

Lloyd Hornbostel, Beloit, Wis., assignor to Beloit
Iron Works, Beloit, Wis., a corporation of Wisconsin

Application August 4, 1950, Serial No. 177,677

3 Claims. (Cl. 29—113)

1

The present invention relates to an anti-deflection roll and more particularly to a roll wherein a roll shell is disposed upon a central shaft for rotation therewith by means of resiliently inflatable supporting elements interposed between the shell and the axle.

In the prior art, many various types of paper machine rolls have been proposed for utilization under deflecting stress, as for example, the bottom roll of a superimposed calender stack. However, such prior rolls have been relatively complicated and have been assembled from a plurality of closely machined expensive parts adapted to mount a roll shell upon an axle in such a manner as to accommodate concurrent axle and shell deformation. Consequently, such rolls have been expensive in both initial and maintenance costs, as well as being complicated in design, manufacture and assembly.

The present invention now provides an extremely simple anti-deflection roll for such use wherein inflatable members are interposed between the roll shell and the roll axle to secure the same together for rotation. The inflatable members are formed of a resilient elastomeric substance, such as natural or synthetic rubber or the like, and the inherent resiliency of the inflatable members, together with the cushioning effect of the inflating fluid, serves to retain the shell upon the axle in such a manner that the smooth running relationship between the roll shell and the axle is preserved even under severe operating conditions causing distortion of either or both of the roll parts.

An additional feature of the present invention is the elimination of the heretofore necessary machining of the means used to retain the roll shell upon the shaft, inasmuch as the inflation of the securing means accommodates irregularities caused or formed during manufacture or use, with the fluid pressure within the inflatable member permitting self-adjustment of the securing means under distorting stress applied to either the axle or the shell, or both.

It is, therefore, an important object of the present invention to provide a resilient inflatable connection interposed between a paper machine roll shell and an axle for the shell for securing the shell to the axle for corotation despite distortion of either the shell or the axle.

Another important object of the present invention is to provide a roll for a paper making machine including a roll shell, a roll shaft passing through the shell and resiliently inflatable means interposed between the shell and the shaft and

2

urged thereagainst under fluid pressure to couple the shell to the shaft for corotation despite distortion of the roll under load.

It is a further important object of the present invention to provide an improved resilient means for securing a roll shell to a central axle, the means being interposed between the shell and the axle and being inflatable under fluid pressure to thereby secure the shell to the axle for corotation with the resilient means and the fluid confined therein under pressure accommodating distortion of the roll assembly from its normal symmetrical configuration.

Still another important object of the present invention is to provide a roll including a generally cylindrical peripheral shell and an axle extending axially through the shell, the shell being secured to the axle for rotation by means of a plurality of resiliently inflatable elements interposed therebetween and urged into contact with both of the members by means of a fluid pressure confined therein.

Other and further important objects of this invention will be apparent from the disclosures in the specification and the accompanying drawings.

On the drawings:

Figure 1 is a sectional view, with parts shown in elevation, taken along the axis of a roll of the present invention;

Figure 2 is a sectional view similar to Fig. 1 illustrating, in exaggerated form, distortion of the roll shell and roll axle when the roll is placed under a load; and

Figure 3 is a sectional view taken along the plane III—III of Fig. 1.

As shown on the drawings:

In Figure 1, reference numeral 10 refers generally to an anti-deflection roll of the present invention including an exterior, generally cylindrical roll shell 11, formed of steel, brass, or other suitable material and having a shaft or axle 12 extending axially therethrough.

The axle 12 is provided with an axial internal bore 13 extending along substantially the entire length thereof and communicating with a source of fluid, such as air, under pressure through a conduit 13a. The terminal end of the bore 13 communicates with a radially extending fluid flow passage 14, while a similar radial passage 15 is provided intermediate the length of the bore 13. The axle 12 is provided with a plurality of pairs of radially extending peripheral shoulders 16 spaced axially on either side of the passages 14 and 15.

Between each of the sets of shoulders 16, there is confined between the axle 12 and the shell 11 a resiliently inflatable tire 17. Each tire 17 is provided with a smooth generally cylindrical outer peripheral surface 18 in extended surface contact with the inner periphery of the shell and with a concentric inner peripheral surface 19 contacting the exterior periphery of the shaft 12 intermediate the shoulders 16. Preferably, the inner surface 19 is of such dimension that the tire, when inflated, fits snugly between the shoulders. The tire 17 is actually toroidal in shape, with the inner annular space 20 being inflatable with the fluid under pressure. Inflation of the space 20 is carried out by means of a radially inwardly extending inflation neck 21 formed integrally with the tire 17 and projecting into the passage 14-15 lying between the shoulders 16 confining the tire.

It will be seen that the inflation neck 21 thus establishes communication between the interior space 20 of the tire 17 and the radial passage 14-15 communicating with the bore 13 which is adapted to receive fluid under pressure to the conduit 14 connected to a suitable source. In this manner, the tire 17 may be inflated with fluid under pressure so as to expand the tire surfaces 18 and 19 into tight engagement with the adjacent periphery of the shell 11 and the shaft 12, respectively.

The extreme simplicity of this method of securing the shell 11 to the shaft 12 will be readily appreciated by those skilled in the art, and the elimination of the excessively expensive, heretofore necessary close machining tolerances will be evident. The resilient inflation of the tire 17 makes possible the accommodation of the tire to any irregularities on the shaft or on the shell inner periphery. Further, the inflation under fluid pressure insures a tight fitting wedged engagement between the tire, shaft, and shell. It will be appreciated that the number of tires disposed within any shell is to be governed by the roll dimensions, and also by the load imposed upon the roll. By utilizing a plurality of such tires, it is feasible to support the load upon the bottom roll of a large calender stack by the utilization of comparatively moderate fluid pressures. In connection with such pressures, it will be appreciated that either a pneumatic or a hydraulic pressure medium may be utilized.

Another advantage of the utilization of an inflatable tire 17 resides in the provision of a cushioning connection between the shell and the shaft. As illustrated in Fig. 2, this fluid cushioning effect will result in true running of the roll, even though the roll is deflected from its normal symmetrical configuration as shown in Fig. 1. The fluid pressure is shiftable to accommodate any deflection of either the roll shaft or the roll shell, and there is no possibility of the rupture of any portion of the roll assembly due to the shifting of the roll components. Also, to remove the shell from the axle for replacement or other purposes, it is only necessary to deflate the tires.

It will be seen that the tire serves as an actual fluid coupling between shaft and shell and the

torsional load imposed on the shaft in starting the roll, or during running, will be accommodated by resilient flexing of the tire, which flexing will be accommodated by the resilient fluid pressure support of the tire itself. Thus, the fluid pressure tire serves to accommodate both torsional and deflectional loads upon the roll assembly, which stresses may be of large magnitude when the roll is utilized in portions of a paper machine, such as in a stack of calender rolls.

It will be understood that modifications and variations may be effected without departing from the scope of the novel concepts of the present invention.

I claim as my invention:

1. A roll assembly comprising a rigid cylindrical outer shell, a rigid through shaft axially received thereby, separate and apart resilient inflated tires adjacent but inwardly spaced from each end of the shell providing the sole support for corotatably mounting the shell on the shaft, said shaft having an axial bore and radial passages communicating with said bore, means establishing communication between said radial passages and said tires, and a fluid pressure source communicating with said bore.

2. A roll assembly comprising a rigid cylindrical outer shell, a rigid through shaft axially received thereby, separate and apart resilient inflated tires adjacent but inwardly spaced from each end of the shell providing the sole support for corotatably mounting the shell on the shaft, spaced grooves in said shaft retaining the inflated tires therein, and conduits in said shaft communicating with said tires at the retaining grooves and extending axially of said shaft for communication with a source of fluid under pressure.

3. A roll assembly comprising a rigid cylindrical outer shell, a rigid through shaft axially received thereby, separate and apart resilient and inflated tires adjacent but inwardly spaced from each end of the shell providing the sole support for corotatably mounting the shell on the shaft, said shaft having an axial bore for communication with a source of fluid under pressure and radial passages communicating with said bore, and means establishing communication between said radial passages and said tires.
